Des. 211,356
Patented June 11, 1968

211,356

CONTAINER FOR STORING AND SHIPPING A REEL OF VIDEO TAPE OR SIMILAR ARTICLE

Raymond W. Jensen, Marina del Rey, Calif., assignor to Comdata Corporation, Los Angeles, Calif., a corporation of California

Filed Jan. 27, 1967, Ser. No. 5,592

Term of patent 14 years

(Cl. D26—14)

FIG. 1 is a perspective view of a container for storing and shipping a reel of video tape or similar article embodying my new design;

FIG. 2 is a rear elevational view thereof;

FIG. 3 is a top plan view thereof; and

FIG. 4 is a side elevational view thereof illustrating the side of the container which is substantially hidden in FIG. 1.

I claim:

The ornamental design for a container for storing and shipping a reel of video tape or similar article, substantially as shown.
